CAST COPING STONE

Mario A. Montesano, 3252 W. Lansing Way,
Fresno, Calif.

Filed Aug. 24, 1964, Ser. No. 81,414

Term of patent 14 years

(Cl. D13—1)

FIG. 1 is a top plan view of a cast coping stone showing my new design.

FIG. 2 is a front elevational view of the stone of FIG. 1.

FIG. 3 is a side elevational view of the stone of FIG. 1.

FIG. 4 is a reduced scale view in rear elevation of the stone of FIG. 1.

FIG. 5 is a reduced scale bottom plan view of the stone of FIG. 1.

FIG. 6 is a perspective view of the stone of FIG. 1.

I claim:

The ornamental design for a cast coping stone, as shown.
